UNITED STATES PATENT OFFICE.

HAROLD W. NICHOLS, OF MAPLEWOOD, NEW JERSEY, ASSIGNEE TO WESTERN ELECTRIC COMPANY, INCORPORATED, OF NEW YORK, N. Y., A CORPORATION OF NEW YORK.

HIGHLY-SELECTIVE CIRCUIT.

Application filed December 31, 1921. Serial No. 526,208.

To all whom it may concern:

Be it known that I, HAROLD WILLIAM NICHOLS, a citizen of the United States, residing at Maplewood, in the county of Essex, State of New Jersey, have invented certain new and useful Improvements in Highly-Selective Circuits, of which the following is a full, clear, concise, and exact description.

10 This invention relates to selective electric circuits and more particularly to networks for selecting a wave of desired frequency from a common medium or circuit carrying disturbing electrical energy.

15 It is old in the art to employ tuned circuits and filters for the purpose of selecting one particular frequency or band of frequencies from a circuit carrying current of disturbing wave frequencies in order to obtain a high degree of discrimination between desired and undesired waves. When high selectivity is required, however, difficulties are encountered in constructing capacity and inductance elements of the requisite constants, inasmuch as the dimensions of these elements approach prohibitively large values as the selectivity is increased. One object of this invention is to obtain a high degree of selectivity without employing bulky or expensive capacities and inductances.

20 In accordance with the present invention a network comprising distributed series and shunt impedance is connected to the source of electric energy from which a particular wave frequency is to be selected. Two or more repeaters are connected to said filter, the control element or grid of each repeater being connected to a different point in said filter, these points being so chosen that, at 25 the desired frequency, the potentials of said grids are in phase with each other and cause the flow through a common output circuit of currents which supplement each other. At any other frequencies than the desired 30 frequency, the potentials of the grids will be in different phase relation to each other and for this reason will produce currents in the output circuit of the repeaters which tend to neutralize each other. The common 35 output circuit of the repeaters is tuned to the frequency wave to be selected thus aiding in the discrimination between desired and undesired wave energy. A receiving circuit is coupled to the common output circuit 40 of the repeaters for the purpose of obtaining

a response from a wave of desired frequency. This combination of the network and repeaters besides being highly selective at some particular frequency discriminates between electric impulses and sustained waves, in view of the fact that impulses will in general excite free oscillations of different frequencies from that of the desired waves.

Other objects of the invention will be apparent from the more detailed description of the invention which follows, taken in view of the appended drawing and claims.

Fig. 1 is a circuit diagram of a generic form of the invention. Fig. 2 is a diagram illustrating a modification of the invention employing a filter having distributed series inductances and shunt capacity. Fig. 3 is a graph illustrating the selective characteristics of a circuit similar to Fig. 2. Fig. 4 is a modified form of the invention in which the filter comprises an aerial or antenna circuit.

Referring to Fig. 1, the source of electrical energy 1, comprises a source of sustained electric waves, and may also include a source of electric impulses. Source 1 may be an antenna, or a line wire such as a signal or power line, and is connected to one end of a network or band filter 2, comprising a plurality of series impedance elements 3, 4, 5, 6, 7, etc., and shunt impedance elements 8, 9, 10, 11, 12, etc., these impedances being composed of capacity, inductance, and resistance in the relation called for in any well-known type of filter, it being understood that any one, or more, of the three constants of capacity, inductance, or resistance may be omitted from any given impedance. The attenuation of the network 2, is preferably made very small, or substantially zero for waves of desired frequency, but it is to be distinctly understood that the principle of this invention may be carried out successfully when a filter or network having appreciable attenuation for the desired waves is used.

A plurality of repeaters 13, 14, 15, etc., each having a cathode 16, an anode 17, and a grid 18, are arranged with their output circuits in parallel and are supplied with space current from the common source 19. Cathodes 16 of the repeating devices are connected through a common source of grid polarizing potential 20 and the network 2

to the grids 18, each grid being connected to the network 2 at a different point 21, 22, 23, etc. The normal potentials of the grids are made negative with respect to the cathodes 16 by the source of potential 20. Points 21, 22, 23, etc., are so chosen in the network 2 that at some given frequency which it is desired to receive, the potential waves at these points will be in phase with each other, angles of 360 degrees and integral multiples thereof not being counted. In other words, at the desired frequency, if the potential at the point 21 be displaced in phase by a given angle from the potential at the lower terminal of the source 1, the potential at the points 22 and 23 will be displaced from said potential at the source 1 by said angle. It will, therefore, be seen that, at the desired signal frequency, the same effect is produced on each of the grids 18, assuming that the network 2 has zero attenuation for waves of desired frequency. When use is made of a network which appreciably attenuates the waves of desired frequency, the amplification of the respective repeaters is adjusted to compensate for the loss in wave amplitude caused by the network.

For frequencies other than the signal frequency to be received, the impedance elements 3, 4, 5, etc., 8, 9, 10, etc., will in general have different phase angles, and for this reason, at any one of said other frequencies, a wave of potential at the point 21 will be out of phase with the wave of potential at point 22 while the wave of potential at point 23 will be out of phase with the waves of potential at the points 21 and 22. It is to be noted that the points 21, 22, 23, etc., are at different electrical distances from the source 1.

Output circuit 25, including inductance 26 and the variable capacity 27, is tuned to the frequency of the waves to be received, while tuned circuit 28 including variable capacity 29 and inductance 30 is tuned to the same frequency as circuit 25. Circuit 28 is connected to the input terminals of a detector or other repeating device 31 which is connected to the receiving circuit 32.

Inasmuch as grids 18 receive potential variations in phase with each other at the desired frequency, while they receive potential variations out of phase with each other at undesired frequencies, the space current variations of desired frequency will be in phase with each other in the tubes 13, 14, etc., and will, therefore, cooperate to produce a maximum current in the winding 26, circuit 28, and receiver 32, while space current variations in said tubes at frequencies other than the desired frequency, being out of phase with each other, will neutralize each other, thereby producing a very small or negligible effect upon the receiver 32. By

adding more sections to the network, of the same character as sections 3, 8; 4, 9; etc., and connecting additional repeating devices to the additional sections of the network in the same relation as in the connections shown, the desired wave frequency will be further supplemented, while undesired frequencies will in general be further neutralized in the common output circuit 25. Although the circuit disclosed, when employing only two repeaters such as 13, 14 in conjunction with the network 3, 8; 4, 9; 5, 10; provides a relatively higher degree of selectivity than the networks 3, 8; 4, 9; 5, 10, alone, the circuit is made more selective by adding sections 6, 11; 7, 12, and repeater 15.

When an impulse is impressed upon the network 2 from the source 1, free oscillations are set up in the network in accordance with the natural free periods of the various closed circuits which can be traced in the network. These free oscillations will, to a great extent, be of frequencies which are different from that of the desired wave frequency, and for this reason, when any one frequency of the free oscillations is considered, the effect thereof will be seen to be largely neutralized in the common output circuit 25 by virtue of the differences in phase of the potential waves acting upon the grids 18. The energy of an impulse impressed by the source 1 upon the network 2 is, therefore, discriminated against by the system as a whole, so that the disturbing energy reaching receiver 32 is very small, or substantially zero.

It is not essential that impedance elements 3, 4, 5, 6, etc., be of equal value, or that impedance elements 8, 9, 10, 11, 12, etc., be of equal value, as in some cases it may be desirable to use different values of said impedances, for example, to permit of a given number of impedances of different values to function similarly to a larger number of impedances of equal value.

Fig. 2 illustrates a specific form of network in accordance with Fig. 1, particularly adapted to discriminate between impulses and waves of some desired frequency and at the same time provide a high degree of selectivity between the desired wave frequency and all other frequencies which may be applied to the network. In this circuit, inductance elements 35, 36, 37, etc., of negligible resistance, are connected in series with the source of electromotive force 1, while capacities 40, 41, 42, etc., of negligible resistance, act as shunt elements in the network 2. The capacities 40, 41, 42, etc., may be considered to include the stray capacities which in effect shunt those shown as, for example, the capacity between the grid and cathode within a repeater. Telephone receivers 43, or other receiving means respond to the desired waves. Other parts of the

circuit are similar in structure and operation to that described in connection with Fig. 1. A network of the type disclosed in Fig. 2, may be designed in accordance with the disclosure in United States patent to G. A. Campbell No. 1,227,113.

Fig. 3 shows the selectivity of a circuit having equal inductance elements and equal capacity elements arranged similarly to Fig. 2, having in this case a filler of eight sections, four repeaters being connected respectively across the second, fourth, sixth and eighth capacities counting from the source 1 and going in a direction away from said source. In this diagram the ordinate of a point on the curve represents the sum of the grid potentials at a given frequency, while the abscissa of said point represents said given frequency, it being understood that the electromotive force of the source 1 is the same for each frequency. The point 45 corresponds to the desired frequency to be received. A wave slightly above or below the frequency corresponding to that of the point 45 is almost completely neutralized, the ordinate corresponding to the points 46 and 47 being very small or substantially zero, as compared to the ordinate of the point 45 corresponding to the desired frequency. Similarly, at other points in the curve corresponding to maxima of the sum of the grid potentials, these sums are very small as compared with the sum at the point 45. It will thus be seen that at one frequency, namely, that corresponding to the point 45, and at only this one frequency, is there any appreciable effect produced upon the common output circuit by the action of the grids. In order to obtain as high a degree of selectivity by an ordinary selective circuit as is obtained by the circuit of Fig. 2, the capacity and inductance elements required would be of much more extreme dimensions than in the circuit shown.

Other forms of networks or filters than those shown in Fig. 2 may obviously be utilized in accordance with this invention. For example, the source 1 may typify a source of received radio waves, and the network 2, an extended radio antenna structure having distributed series inductance and shunt capacity, or distributed series impedance of any form, together with shunt impedance of any form. An example of such an antenna structure is shown in United States patent to Lloyd-Espenschied No. 1,353,735, September 21, 1920.

In Fig. 4 the network A corresponding to the filters 2 of Figs. 1 and 2 comprises an antenna having lumped series impedance elements L_s , C_s and lumped shunt impedance elements L_g . A source of received radio waves is represented by the broken arrow. Shunt distributed capacity of the antenna is represented by the dotted condensers whereas dis-

tributed series impedance is inherent in the conductors connecting the lumped series impedances. The network AN is immaterial in this invention and may be omitted if desired.

70

The terms "repeater" and "repeating device" as employed herein are used for convenience to cover any form of unilateral device capable of reproducing in its output circuit, with or without magnification, an energy change similar to the one impressed upon its input circuit, and may produce in addition thereto, other energy changes than those impressed upon the input circuit.

75

Although the invention has been disclosed showing grid connections at points separated by two sections of a network, it is to be understood that one section or any desired number of sections may intervene between any two adjacent grid connections. Other modifications of the invention than those shown in the drawing are obviously dominated by the generic principle disclosed herein. Features of the invention which are believed to be novel are covered in the appended claims.

80

What is claimed is:

1. In a selective system, a source of electric waves, a plurality of repeaters controlled by said source, a network having a plurality of sections connected between said repeaters and said source, said repeaters having individual input circuits connected to separate points in said network in such manner that, for desired frequencies, the energy supplied to respective repeaters is in phase, and for undesired frequencies the energy supplied to respective repeaters is out of phase, whereby energy of said undesired frequencies is substantially excluded from an output circuit connected to said repeaters.

95

2. In a selective system, a source of electrical waves, a plurality of repeaters associated therewith, and phase shifting means connected between said source and said repeaters to apply to a plurality of said repeaters a wave of undesired frequency from said source in a plurality of different phase relations with respect to the phase of said wave applied to one of said repeaters, and a common output circuit associated with said repeaters to receive waves of desired frequency.

100

3. In a selective system, a source of electric waves, a plurality of repeaters associated therewith, and phase shifting means connected between said source and said repeaters to apply to each of said repeaters a wave of desired frequency from said source in the same phase relation, and to apply waves of undesired frequencies to each of said repeaters in different phase relations with respect to each other, and a common receiving circuit for said repeaters.

110

115

120

125

130

4. In a selective system, a source of electric waves, a plurality of repeaters associated therewith, and phase shifting means connected between said source and said repeaters to apply to each of said repeaters a wave of desired frequency from said source in the same phase relation, and to apply waves of undesired frequencies to each of said repeaters in different phase relations with respect to each other, a common output circuit for said repeaters, and receiving means associated with said output circuit.
5. The method of selectively translating electrical waves which comprises establishing certain waves corresponding in frequency but differing in phase from each other, and other waves corresponding both as to frequency and phase, and combining said certain waves to cause mutual neutralization of their effects and combining said other waves to cause cumulation of their effects.
6. In combination, a source of electric waves, a bilaterally conducting, selective network connected to said source, a repeater connected to said network, and a plurality of other repeaters independently connected to said network, each at a different electrical distance from said source than said first-named repeater, and a common output circuit for all of said repeaters.
7. The method of increasing selectivity in the translation of electric energy which comprises separating energy of undesired frequencies into a plurality of components each having a different phase relation, combining said components to cause mutual neutralization of their effects, and increasing the number of components of said energy of undesired frequencies sufficiently to produce the desired selectivity.
8. In a selective system, a source of electric energy, a bilaterally conducting circuit comprising a distribution of lumped series and shunt impedances connected to said source, a plurality of repeaters greater in number than two, each independently connected to said circuit at a different point therein, and a common output circuit for said repeaters.
9. In a selective system, a source of electric energy, a circuit comprising a distribution of lumped series inductance and shunt capacity connected to said source, a plurality of repeaters greater in number than two, each connected to said circuit at a different point therein, and a common output circuit for said repeaters.
10. In a selective system, a source of electric current, a circuit comprising a distribution of series inductance and shunt capacity connected to said source, a plurality of repeaters greater in number than two, each connected to said circuit at a different point therein, and a common output circuit for said repeaters tuned to the frequency of a wave to be selected from said source.
11. A receiving system comprising an input source of energy, a bilateral electrical network associated therewith and composed of a plurality of sections serially connected, and a plurality of repeater devices having input circuits associated with said network, each having its input circuit connected thereto at a different point, said repeaters and network being so related that the number of repeaters and sections of said network may be indefinitely increased to improve the operation of the system, and common receiving means associated with said repeaters.
12. A receiving system comprising an input source of energy, a continuous homogeneous electrical network associated therewith and composed of a plurality of sections serially connected, a plurality of repeating devices, greater in number than two, each connected to a different point in said network, and common receiving means associated with said repeaters.
13. In combination, a plurality of electric wave repeaters having separate input circuits and a common output circuit, a source of electric energy associated with said input circuits, and means provided between said source and said repeaters for impressing undesired electric variations from said source upon successive repeaters in successively different phase relation, and for impressing desired variations thereupon in the same phase relation.
14. In combination, a plurality of electric wave repeaters having separate input circuits and a common output circuit, a source of electric energy associated with said input circuit, means provided between said source and said repeaters for impressing undesired electric variations from said source upon successive repeaters in successively different phase relation, and for impressing desired variations thereupon in the same phase relation, and receiving means associated with said common output circuit.

In witness whereof, I hereunto subscribe my name this 27th day of December, A. D., 1921.

HAROLD W. NICHOLS.
